UNITED STATES PATENT OFFICE.

SILAS TUTTLE, OF NEW YORK, N. Y., ASSIGNOR TO TUTTLE & BAILEY MANUFACTURING COMPANY, OF BROOKLYN, NEW YORK, A CORPORATION OF NEW YORK.

HOT-AIR REGISTER.

REISSUED

SPECIFICATION forming part of Letters Patent No. 737,976, dated September 1, 1903.

Application filed March 16, 1903. Serial No. 147,961. (No model.)

To all whom it may concern:

Be it known that I, SILAS TUTTLE, a citizen of the United States, and a resident of the city of New York, (borough of Brooklyn,) in the county of Kings and State of New York, have invented a new and Improved Hot-Air Register, of which the following is a full, clear, and exact description.

This invention relates to improvements in registers designed to be placed in the side walls of a room for the diffusion of hot air, and an object is to secure an enlarged opening from the lower room to the upper by projecting the register some distance into the room, thus allowing a portion of the floor to be cut out for a larger pipe than can be passed up through the ordinary partition.

Another object is to control the air delivered by directing it wholly, partly, or not at all into either the lower or upper room, as may be desired.

Another object is to provide a simple and convenient means for operating and holding the damper as adjusted to produce the above result.

Another object is to provide a simple and effective method of fastening the register to the wall without exterior screws or nails and which shall also form a connection adjustable to the varying thicknesses of lath and plaster between the flue and the face of the wall against which the register is placed, as herein-after described.

Another object is to so construct the damper that it will not be distorted by heat and be generally of increased strength to resist abuse.

I will describe a register embodying my invention and then point out the novel features in the appended claims.

Reference is to be had to the accompanying drawings, forming a part of this specification, in which similar characters of reference indicate corresponding parts in all the figures.

Figure 1 is a perspective view of a register embodying my invention. Fig. 2 is a section thereof on the line 2 2 of Fig. 3. Fig. 3 is a section on the line 3 3 of Fig. 2 with a part broken away, and Fig. 4 is a sectional view of the damper.

Referring to the drawings, 5 designates the frame of the register, which is made deeper at the bottom than at the top, allowing a tin flue to be placed having double the capacity in its lower portion than at its upper portion 55 in the register. The register-frame is placed against the face of the wall at the floor after removing a portion of the base-board. The tin box 9, formed to receive the register, is brought through the opening of the frame, 6c the edges are trimmed to suit the thickness of the wall, and the edges are then turned over the frame. The face-plate and the damper are then replaced and screwed firmly against the tin, thus holding the register 65 securely in position.

In the front of the frame is removably placed the grille face 6. This grille face 6 is held in place by means of screws 7. The damper 8 is designed to swing relatively to the face 6, so as to effectually cut off the passage of hot air through said face or to direct it through the face, wholly or partially cutting off the register box or flue 9, to which the frame 5 is attached. It may be here stated that this 75 damper 8 is concaved both transversely and lengthwise. By this means it is practically impossible to distort the damper by heat or abuse, as often happens with flat dampers. At its upper portion the damper has trunnions 10 for engaging in bearing-sockets 11, formed on the inner side of the frame, and it will be noted that the face 6 forms a front bearing for the trunnions and holds the same in place. At its sides, near the top, the 80 face 6 is provided with inwardly-extended brackets 12, on which the trunnions may rest when placing the same in the socket-bearings, as will be hereinafter described. At one end, near the top, the face 6 is provided with a slot 90 13, in which a lever 14 is pivoted. The inner portion of this lever is provided with a slot 15, which is eccentric to the pivot of the lever, and in this slot a pin 16 extends from the damper. 95

In the operation of this part of the invention by pressing downward on the outer end of the lever 14 the damper 8 may be swung to and held in any desired open position. Of course by moving the outer end of the le- 100

ver in the opposite direction the damper will be swung to and held in closing position.

In assembling the parts the trunnions 10 of the damper are to be supported on the brackets 12 and the damper held closely against the face 6 with the pin 16 in the slot 15. Now the trunnions may be readily inserted in the socket-bearings 11 and the front plate placed in position and secured by means of the screws 7.

Having thus described my invention, I claim as new and desire to secure by Letters Patent—

1. In a register, a frame having socket members forming bearings opening outward, a damper, trunnions on said damper for engaging in said socket members, a front plate secured to the frame and forming outer bearings for the trunnions, and brackets on the

inner side of the front plate for supporting the damper when assembling the parts. 20

2. In a register, a frame having socket members forming bearings, the said socket members opening outward or to the front, a damper, trunnions on said damper to engage in 25 said socket-bearings, a grille front removably secured to the frame and forming the outer bearings for the trunnions, and brackets on the inner side of said grille front for supporting the trunnions when assembling the parts. 30

In testimony whereof I have signed my name to this specification in the presence of two subscribing witnesses.

SILAS TUTTLE.
